EASEL

Leo L. McKeown, Toledo, Ohio, assignor to Geo. L. Kohne, Inc., Toledo, Ohio, a corporation of Ohio

Application May 29, 1939, Serial No. 276,450

3 Claims. (Cl. 248—35)

The invention relates to easel supports designed for application to pictures, picture frames and similar articles. It is the object of the invention to obtain a construction which is readily attachable to the article to be supported; which when not in use will lie flat in parallelism with said article; and which in use will be locked in rigid supporting relation thereto. To this end the invention consists in the construction as 10 hereinafter set forth.

In the drawing:

Figure 1 is a rear elevation of my improved easel support in collapsed position;

Figure 2 is a side elevation showing the support extended for use;

Figure 3 is a plan view indicated in full lines the collapsed position and in dotted lines the open position;

Figure 4 is a horizontal section on line 4—4 20 of Figure 1.

My improved easel support may be formed from any suitable sheet material, but preferably heavy cardboard. The blank A is preferably cut to taper in an upward direction with 25 parallel upper and lower edges B and C. A short distance below the upper edge the blank is provided with one or more scores D and D' to facilitate bending. From the center of the blank below these scores is cut a brace member E which 30 has a wide portion E' at the bottom tapering upwardly to a narrower neck E², then flaring outward to a wider portion E³, again tapering to a narrow portion E⁴, and again widening to a portion E⁵. Adjacent but slightly below the narrow neck E² are angle portions E⁶ having a dimension between them slightly greater than the restricted portion E⁴. This brace portion is completely severed from the remainder of the blank, but when attached to the article to be supported 35 is in its original position. The portion E' below the narrow neck E is rigidly attached to the back of the article to be supported by any suitable means, such as by one or more staples F or by the use of adhesive. Also, the portion of the 40 main blank above the score D is secured to the back of the article to be supported, in a similar manner by staples G. This permits the blank to lie flat against the back of the article to be supported. To place the device in condition for 45 use the main blank A is moved outward from its lower end leaving the brace member E in its original position. The brace member E is then drawn outward from its upper end bending at the narrow neck E², which bending is facilitated 50 by a score E⁷ at this point extending transverse-

ly across the brace. When the upper end of the brace is sufficiently lowered to register with the opening from which the portion E' has been removed, it will enter this opening after which the brace may be drawn upward to engage the 5 restricted portion E⁴ with the notches E⁸ formed by the removal of the angle portions E⁶. This will form an interlock and there will be sufficient resiliency in the brace member to press it upward and to maintain engagement with said 10 notches. In this position of the parts the main portion of the blank forms an inclined supporting leg which is held spaced from the back of the article to be supported and in rigid relation thereto.

Another and preferable method of placing the device in condition for use is to first pull outward the brace member from the aperture in the remainder of the blank. This is facilitated by cutting away the upper end of the brace member, 20 as shown in Figure 1, thereby forming an aperture in which a finger or thumb may be inserted for engaging the nail with the upper edge of the remaining portion of said brace. The brace may then be drawn outward far enough so as 25 to permit the remainder or leg portion of the blank to also be drawn out, the upper and intermediate portions of the brace being movable through the aperture left by the wider base portion of said brace. Thus the narrow portion 30 E⁴ may be registered with the notches E⁸, whereupon the resiliency of the brace member will press it upward into interlocking engagement therewith.

What I claim as my invention is:

1. An easel support comprising a flat blank of resilient material adapted to lie parallel to the back of the article to be supported with its upper end portion secured thereto, and a brace severed from the central portion of said blank 40 having its lower end portion of greater width than its upper end portion and the latter of greater width than an intermediate portion, said blank being scored for bending between said lower and intermediate portions and said lower end portions being secured to said back while said brace is in its original relation to the blank and parallel to said back, the upper end portion being bendable downward along the scored line to be movable through the aperture formed by 45 the removal of the lower end portion and being notched for interlocking engagement with the sides of the intermediate portion of said aperture and held in such position by the resiliency of the material.

2. An easel support comprising a flat blank of resilient material adapted to lie parallel to the back of the article to be supported with its upper end portion secured thereto, and a brace severed from the central portion of said blank having its lower end portion of greater width than its upper end portion and scored for bending adjacent thereto also having an intermediate portion of lesser width than said upper portion fashioned to form notches in the opposite sides of the aperture formed when the brace is removed, said upper end portion of the brace being bendable downward along the scored line to be movable through the wide aperture formed in the blank 5 by the removal of the lower end portion of the brace and being notched in its opposite sides for interlocking engagement with said notched sides of the aperture in the blank and held in such position by the resiliency of the material.
- 10 3. An easel support comprising a flat blank of resilient material adapted to lie parallel to the back of the article to be supported with its upper end portion secured thereto, and a brace severed from the central portion of said blank having its lower end portion of greater width than its upper end portion and scored for bending adjacent thereto also having an intermediate portion of lesser width than said upper portion fashioned to form notches in the opposite sides of the aperture formed when the brace is removed, said upper end portion of the brace being partly cut away to leave an opening for engaging a finger nail with the upper edge of the remaining portion so as to pull the same outward being also movable through the wide aperture formed in the blank by the removal of the lower end portion of the brace and being notched in its opposite sides in registration for interlocking engagement with said notched sides of the aperture in the blank, said blank and also said brace being scored intermediate the attached and free portions thereof to facilitate bending downward and the resiliency of the material of the brace pressing it upward into 10 interlocking engagement.
